W. R. BUXTON

KEY CASE

Filed Sept. 6, 1923

FIG. 1.

INVENTOR
Warren R. Buxton
BY Chapman & Neal
ATTORNEYS

UNITED STATES PATENT OFFICE.

WARNER R. BUXTON, OF LONGMEADOW, MASSACHUSETTS, ASSIGNOR TO BUXTON INCORPORATED, OF SPRINGFIELD, MASSACHUSETTS, A CORPORATION OF MASSACHUSETTS.

KEY CASE.

Application filed September 6, 1923. Serial No. 661,296.

This invention relates to improvements in key cases and is more particularly directed to improvements in the case itself as distinguished from the key holders and the manner of mounting them.

The invention also is directed to improvements in the structure disclosed in my prior U. S. Letters Patent No. 1,443,937 granted January 30, 1923. In this patent, there is disclosed a member provided with a pocket to receive articles such as identification tags, automobile license and registration papers and so forth, which member is pivotally connected to the case so that access 15 may be had to the pocket on the rear side of the member. Such member may also have a bracing or stiffening function, the advantages of which are fully disclosed in said prior patent.

20 The key case of such patent, however, is specially constructed for its special purpose, and differs considerably from the standard key case. The key holder plate is not attached to the back of the case, as is usual, but is attached to the swinging and pocket-forming member. Also, such member is pivotally connected to the back of the case by stitching and the weight of the keys comes directly on the stitched seam, which 25 may in time weaken and shorten the useful life of the case.

This invention has for its object the provision of means which can be quickly and conveniently attached to a standard key case 30 to convert it into one of the so-called "auto license" type or into one having an identification tag or the like.

The invention has for another object to provide a carrier which is detachably connected to the case, preferably to the key holder plate thereof, for swinging movement and such carrier may be utilized for the purposes above described or any other purpose desired.

45 The invention has for another object to provide a carrier, in the nature of a wire loop, having trunnions or the like, to fit into the open ends of the hollow cylindrical member, usually provided in a key case for the 50 purpose of supporting the key holders.

According to some features of the invention, the stiffening function, alluded to in

the above identified prior patent, may also be accomplished by the structure disclosed herein.

55 Other objects and advantages will appear in the following description and in the illustrative embodiment of the invention in the accompanying drawings, in which:

Fig. 1 is a front elevational view of an 60 open key case showing one embodiment of the invention;

Fig. 2 is a sectional elevational view of the key case shown in Fig. 1;

Fig. 3 is a view, taken similarly to Fig. 65 1, showing another embodiment of the invention;

Fig. 4 is a sectional elevational view of the key case shown in Fig. 3;

Figs. 5 and 6 are enlarged and fragmentary top plan views showing the means for 70 detachably connecting the carrier, shown in Fig. 3, to the key holder plate; and

Fig. 7 is an enlarged fragmentary elevational view, partly in section, showing a 75 modification in the carrier shown in Fig. 1.

Referring to these drawings; the case itself is desirably constructed in the same general manner as disclosed in my prior patent, above identified, and, as illustrated, consists of a strip 10, the end portions 11 of which constitute flaps adapted to be folded in overlapping relation over the central portion 12, which constitutes the back of the case. The flaps 11 may be detachably 85 secured together by any suitable means, such as the male and female fasteners 13 and 14, respectively.

The key holders, represented conventionally at 15, may be of any desired type and 90 they may be mounted in the case in any suitable way. As shown, the key holders 15, which are snap hooks, are mounted in a hollow cylindrical member 16 for both swinging and swivelling movement. This 95 member 16, which is open at each end, is preferably part of a metal plate 17 which is rigidly secured to the back 12, as by rivets 18.

The carrier, represented generally at C, is 100 usually in the nature of a cross-bar 20, having upwardly extending side portions 21 which terminate with inturned portions 22 forming trunnions. These trunnions are

adapted to be received in the open ends of the hollow transversely disposed member 16 and in such a manner as to permit the carrier C to swing relatively thereto. The carrier, according to some features of the invention, may be utilized to carry anything desired.

The carrier may also vary considerably according to the purpose for which it is used 10 and may be relatively long, as shown in Fig. 1, or relatively short, as shown in Fig. 2. Various expedients may also be employed for pivotally connecting the carrier to the case; and the particular expedient 15 employed will vary according to the nature of the carrier. With one, such as shown in Fig. 1, the carrier may be formed of relatively small wire possessing sufficient resiliency so that the sides 21 may be sprung 20 outwardly away from one another to a sufficient degree to permit insertion or removal of the trunnions 22 in member 16.

However, with a carrier, such as that shown in Fig. 3, the arrangement just described is manifestly not feasible and, in this case, a slot 23 is provided in each end of member 16. These slots are preferably located in the upper portion of member 16, and extend axially thereof from points near 30 its ends to such ends. The trunnions are then inserted or removed by passing them through the slots 23. In this connection, I prefer to make the sides 21 of the carrier so short that the cross-bar 20 thereof will 35 abut the lower peripheral portion of member 16 and prevent the trunnions 22 from passing through the slots when the parts are positioned as shown in Fig. 3. Moreover, the trunnions 22 need not be exactly 40 cylindrical and in fact may be flattened somewhat as shown in exaggerated form in Figs. 5 and 6. In such case, each slot 23 will be made comparable in width with the narrow side 24 of the trunnion and so that 45 the wider side 25 of the trunnion cannot pass therethrough. The wider sides 25 of the trunnions are preferably located at the top and bottom thereof, whereby the carrier cannot be dislodged, while in the illustrated 50 position or any other position in which it is normally at rest. The arrangement is such that the carrier can be detached at an intermediate point in its range of swinging movement, at which time the narrow sides 24 55 are so positioned as to pass through slots 23.

The arrangement just described can be used, if desired, in connection with the carrier shown in Fig. 1 and may be desirable when the carrier is made of heavier material 60 and incapable of being mounted and dismounted in the manner first above described. Such an arrangement is shown in Fig. 7 and the sides 21 of the carrier may be bent to form inwardly extending shoulders 26 which 65 are adapted to abut the member 16 and pre-

vent the trunnions from passing through slots 23.

In the form shown in Fig. 1, the carrier 20 has mounted upon its cross-bar a case 27, having a pocket therein to receive an identification tag 28 and a window 29 through which such tag is visible. This case 27 is not coextensive in area with back 12 but it may be, and preferably is, coextensive in width therewith to obtain the bracing and 70 stiffening function disclosed in the above named patent. The location of the case 27, at or near the lower part of the back 12, affords less restriction to the keys and permits the back to bulge outwardly at or near 75 its central portion to accommodate the bulkiest portion of the keys, which comes at that location on back 12 unoccupied by the case 27.

The carrier, on the other hand, may have a relatively long flexible member 30 on the 80 rear face of which is attached, near its lower end, a shorter piece 31 of similar material, which is preferably attached to member 30 along three edges, as by stitching 32, thereby forming a pocket open at its upper end. 85 The arrangement is then generally similar to that disclosed in my prior patent with the exception that it is detachable from the case. An eyelet 33 may be passed through the members 30 and 31, near their lower ends, 90 to receive a retaining chain. With this arrangement, it is preferred to offset the cylindrical portion 16 as shown in Fig. 4 so that the key holders 15 may hang vertically as 95 shown. 100

It will thus be seen that the invention provides a means, whereby a standard key case may be converted into one of the auto license type or one having an identification tag or one having a carrier used for other purposes. 105 The manufacturer can take a standard key case and apply to it a carrier like that shown in Fig. 1, or like that shown in Fig. 2, or of some other type, and without much trouble satisfy the wishes of the customers which are 110 many and various. Each user of a key case usually has some individual whim that he wants to satisfy and this invention enables the manufacturer to go part way, at least, in satisfying the individual wishes without 115 manufacturing a large and varied assortment of special cases.

The invention has been disclosed herein, in an embodiment at present preferred, for 120 illustrative purposes, but the scope of the invention is defined by the appended claims rather than by the foregoing description.

Claims:

1. In a key case, a flexible case forming member having a back portion and flap portions cooperating therewith to afford an enclosure for the keys, a rigid member secured to said back across the upper end thereof, a member of flexible material pivotally connected to the second named member and 125

having a part disposed across the back near its lower end and provided with a pocket.

2. In a key case, a flexible case forming member having a back portion and flap portions cooperating therewith to afford an enclosure for the keys, a rigid member secured to said back across the upper end thereof, a member of flexible material pivotally and detachably connected to the second named member and having a part disposed across the back near its lower end and provided with a pocket.

3. In a key case, a flexible case forming member having a back portion and flap portions cooperating therewith to afford an enclosure for the keys, a rigid member secured to said back across the upper end thereof, a member of flexible material pivotally and detachably connected to the second named member and having a part disposed across the back near its lower end and provided with a pocket, the sides of said part adapted to lie substantially coincident with the lines of fold of said flaps.

25 4. In a key case, a flexible case forming member having a back portion and flap portions cooperating therewith to afford an enclosure for the keys, a rigid member secured to said back across the upper end thereof, a member provided with a pocket, and a carrier therefor pivotally connected to said second named member.

5. In a key case, a case forming member having a back portion and flap portions cooperating therewith to afford an enclosure for the keys, a rigid member secured to said back across the upper end thereof, a third member, a cross bar on which the last named member is mounted, said cross-bar having

40 its end portions turned upwardly, and means

provided at the extremities of said end portions for detachable and pivotal connection with the second named member.

6. In a key case, of the type wherein the key holders are supported from a hollow transverse member open at each end, a carrier having trunnions adapted for reception in the open ends of said member to pivotally connect the carrier thereto.

7. In a key case, of the type wherein the key holders are supported from a hollow transversely disposed member open at each end, a carrier having trunnions detachably connected to said member and pivotally received in the open ends thereof.

8. In a key case, of the type wherein the key holders are supported from a hollow transversely disposed member open at each end, a carrier formed of wire having a substantially transversely disposed carrying portion with upwardly extending side portions terminating with trunnions for detachable and pivotal connection with the open ends of said member.

9. In a key case, of the type wherein the key holders are supported from a hollow cylindrical member open at each end, a slot provided in the peripheral portion of said member at each end and disposed longitudinally thereof, and a carrier having trunnions adapted when in one position to pass through said slots and enter into said hollow member to pivotally connect the carrier therewith, said trunnions when the carrier is turned to other positions being incapable of passing through said slots.

In testimony whereof I have affixed my signature.

WARNER R. BUXTON.
